CLAIM

The ornamental design for a footwear article, as shown and described.

DESCRIPTION

FIG. 1 is a front, first side perspective view of a footwear article;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The ornamental design that is claimed is shown in the images in the drawings. The evenly-spaced broken lines depict portions of the footwear article that form no part of the claimed design. The dot-dash broken lines depict the boundaries of the claimed design with the dot-dash lines forming no part thereof.
